CLAIM

The ornamental design for a hidden belt, as shown and described.

DESCRIPTION

FIG. 1 is a rear elevational view of a hidden belt showing my new design;

FIG. 2 is a rear elevational view thereof, the broken line showing of an additional configuration of the belt loop is for illustrative purposes only and forms no part of the claimed design;

FIG. 3 is an exploded front elevational view thereof, the buckle is enlarged for ease of illustration;

FIG. 4 is a front elevational view thereof; and,

FIG. 5 is a front elevational view thereof.

The broken line showing of the pants and one long belt loop is for illustrative purposes only and forms no part of the claimed design.
